[57] CLAIM

The ornamental design for a chair, as shown and described.

DESCRIPTION

FIG. 1 is a front perspective view of a chair showing my new design;

FIG. 2 is a front elevational view thereof;

FIG. 3 is a top plan view thereof;

FIG. 4 is a bottom plan view thereof;

FIG. 5 is a right elevational view thereof;

FIG. 6 is a left elevational view thereof;

FIG. 7 is a rear elevational view thereof;

FIG. 8 is a front perspective view of my chair having a modified back and seat thereof; and,

FIG. 9 is a front perspective view of my chair having another modified back and seat thereof.

The undisclosed views for FIG. 8 correspond to those referenced to FIG. 1. The undisclosed views for FIG. 9 correspond to those referenced to FIG. 1 except that the rear of the center backrest panel is flat.

1 Claim, 9 Drawing Sheets
